UNITED STATES PATENT OFFICE.

CONRAD KAHLER, OF CHICAGO, ILLINOIS.

PRINTING-PRESS FOLDER.

SPECIFICATION forming part of Letters Patent No. 276,972, dated May 1, 1883.

Application filed November 6, 1882. (No model.)

To all whom it may concern:

Be it known that I, CONRAD KAHLER, residing at Chicago, in the county of Cook and State of Illinois, and a citizen of the United States, have invented a new and useful Improvement in Printing-Press Folders, of which the following is a full description, reference being had to the accompanying drawings, in which—

- 10 Figure 1 is a top or plan view, omitting the driving-gear; Fig. 2, a longitudinal vertical section on line $x x$ of Fig. 1; Figs. 3, 4, and 5, details of the guide or switch; Figs. 6 and 7, details of the stop; Fig. 8, a longitudinal vertical section on line $x x$ of Fig. 1, showing the application of a modified form of the guide; Fig. 9, a detail showing the form of the guide; Figs. 10 and 11, details of stop, with a roller or rod for preventing vibration of the tapes at 15 or near the stop; Fig. 12, longitudinal vertical section on line $x x$ of Fig. 1, showing a modified form of the guide in which it is rotary; Fig. 13, a top or plan view, showing the means for operating or driving the rotary guide.

The object of this invention is to provide a simple and efficient means for accumulating sheets within or by the delivery-tapes of a folder or printing-press, so as to deliver two or 20 more accumulated sheets by the continued operation of the same tapes.

The invention consists essentially in the combination, with upper and lower traveling tapes, of a divider arranged to direct the front edge 25 of an advancing sheet past or by the rear edge of a sheet which has previously entered between the tapes and been stopped in its movement, whereby two or more sheets can be accumulated directly upon each other to be folded 30 together or for other purposes. The invention embraces other features, which will be fully hereinafter described, and set forth in the claims.

In the drawings, A indicates the frame-work; 35 B C, the cutting-cylinders of a printing-press, which will usually be attached to the frame-work of the press and will always be attached to the press-frame when the folder-frame is made removable from the press; D, the breaking-roller; E F, end shafts for the tapes; G, elevated shaft for the return of the upper tapes;

H I, shafts for the inner or front ends of the upper and lower tapes; J, the tape-dividing roller; K, shaft upon which the cam-wheels are mounted; L, cam-wheel for driving the guide-rod with its fingers or dividers; M, cam-wheel for operating the stop, with its stop-fingers; N, cam-wheel for operating the upper or first folding-blade of the folder; O P, upper or first pair of rollers of a folding-machine; Q, folder-blade; R, gear-wheel for operating the gear-wheels S T, &c.; S, T, U, and V, bevel-wheels; W, shaft, the gear-wheels and shaft being for the purpose of giving the guide-shaft a rotary motion; X, roller or plate for preventing undue vibration of the tapes; a, guide rod or shaft; b b' b'', guides or dividers; c, arms for rocking the shaft a; d, rod connecting the arm c with the cam-wheel or disk L and for rocking the shaft a; e, spring for giving the rod d its return movement; f g, stops for giving the spring e its operation on the rod d; h, roller on the end of the rod d, working against the cam-wheel or disk L; i, rod or shaft for operating the stops; j, stops; k, arm for operating the rod i; l, rod connecting the arm k with the cam-lever n; m, spring on the rod l for giving the rod or shaft i its return movement; n, cam-lever, operated by the cam o on the wheel or disk M; o, cam on disk M; p q, stops for giving the spring m its proper operation on the rod l; r, upper tapes, and s lower tapes.

The frame A may be made in the form shown or of such other form and dimensions as will 85 be suitable to adapt it to the press and room in which the folder is to be placed for operation.

The rollers B C, as before stated, will belong to the printing-press when the press and folder are not supported in the same frame. When the press and folder are built together, then they will be connected as shown, otherwise secondary posts for supporting the tape-rollers H I will be required; but the application of such secondary posts will be made so as to bring these two rollers in reference to the rollers B C in the position shown. It will be understood that the folder here shown is designed to be used in connection with a perfecting web-printing press, or a press printing upon paper carried in by the press from 90 95 100

the roll without cutting or severing until it is printed on both sides, and for this reason I have shown the breaking-roller D, which said roller will not be required in presses where the paper is fed in sheets, but it will not injure the operation of the machine even for that class of work, as it prevents vertical vibration of the tapes at this point.

The shafts E, F, G, H, and I, which carry the tapes, are provided with the usual tape or belt pulleys, and the ordinary tape-tighteners, (not shown) are to be provided.

The rollers O P are the upper rollers of an ordinary folder, and such additional rollers as will give the desired number of folds will be placed below them. As I have not improved this part of the folder, I have only shown one pair of folding-rollers with their accompanying folding-blade Q. In rear of the breaking-rollers D J, and in proximity thereto, is placed the shaft a for operating the dividers, switches, or guides b b' b'', which rod is suitably supported and journaled in the frame. It is provided with the switch or guide fingers b, which guide-fingers are provided with heels or rear projections for holding up the rear ends of the sheet or half-sheet of paper which is passed over them, which sheet is stopped by the plates j before it is passed entirely off from the heels of the fingers or blades b, so that when the sheet or half-sheet passes under these fingers or blades it will be certain to pass under the sheet which has preceded it, and is there resting against the stop. In the modification of these fingers shown at Figs. 8 and 9, the shaft a is placed over both sets of tapes, and the fingers or guides b' work from above and are made curved, so as to act as hooks for hooking the rear edge of the first sheet or half-sheet, which has been stopped, to insure the under passage of the following sheet or sheets. The rocking of the shaft will in its movements alternately drop and pick up the rear edge of the stopped sheets, so that by the use of this form of fingers on the shaft more than two sheets or half-sheets of paper can be cumulated, whereby a newspaper of five sheets or twenty pages or more can be folded and cumulated without any additional devices for cumulating sheets or half-sheets other than those required for the first two.

In the form of fingers shown in Figs. 12 and 13 the shaft a is placed below both sets of tapes, but in about the same relative position to the breaking-roller. In this form, as in the form shown in Fig. 8, the machine is to be so timed as to lift the rear edge of the stopped sheet or sheets, so that the advancing-sheet will pass under the stopped sheet or sheets and will let the sheets down again upon the lower set of tapes. In this form b'' the shaft a is made rotary instead of being made to rock or vibrate, and I have shown at Fig. 13 suitable gearing for rotating it and timing it to lift the rear edge of the sheet or sheets at the proper time for the advancing sheet or

half-sheet to pass under the stopped ones, and as in this rotary form the fingers move in their travel in the same direction as the printed sheets they can be made to operate when the printed sheets follow each other with only a narrow space between them, and as these fingers b'' do not pass into or out of any space they move along and get out of the way. The object of these several forms is to cause the advancing sheets to pass under the stopped ones.

The stop rod or shaft i crosses the folder, and is suitably supported and journaled in its frame-work. This rod is located below the tapes, immediately below the lower ones, and is provided with the plates or fingers j, which operate between all or a portion of the tapes, and cross the space between the two sets, as shown. This rod may be located above the tapes; but I prefer the position below, as shown, for the reason that it is designed to be turned as soon as the last sheet to be cumulated reaches it, the upper ones having been brought to a full stop, and in starting have a sufficient time to resume their original movements, so as to take the same speed as the lower ones. I also prefer the rocking movement of the stops; but it is evident that by causing the rod l to work a cam or other suitable device a vertical reciprocating movement could be given to the plates j. When located as shown the rod or shaft i is rocked by the arm k, the connecting rod or link l, and the cam-lever n, the upper end of which lever is provided with an anti-friction roller. As the cam-wheel M revolves the short arm of the lever n is held out, as shown, which position throws the long arm of the lever forward and holds the stops j in the vertical position shown for stopping the sheets in their path of travel. As the wheel M rotates the short arm of the lever n drops into the depression o and brings the springs m into operation, which, by means of the arm k, rocks the shaft i and throws the stop down into the position shown in Fig. 7. The spring m is operated by the pendant or support p, which is attached to the frame, and the stop q, which is attached to the rod. There is the same arrangement for the spring e, pendant f, and stop g on the opposite side, working in connection with the cam-wheel or disk L, for rocking the shaft a at the proper intervals of time.

The stops g q may be provided with screw threads, so as to increase or diminish the tensions of the springs e m.

The action of the rod d and its spring is the same as that of the rod l, except that it may have a direct connection with the cam-wheel L by its anti-friction wheel h, Fig. 1, the spring e being arranged to hold the rear end of the said rod against said cam-wheel L.

When the shaft a is made rotary, as shown in Figs. 12 and 13, then the gearing shown in Fig. 13 is added, and the devices for rocking the shaft a shown in Fig. 1 may be omitted,

as it is not necessary to give both movements in the same machine.

I have stated the advantages of the guides or fingers b' b'' to be that a greater number of printed sheets than two could be cumulated; but two sheets, as well as a greater number, can be cumulated by the use of these two forms of guide-fingers.

The tapes r s are arranged substantially as shown; but they will be subject to such variation as the differences in the construction of the frame-work may make necessary.

The parts not fully described may be of the ordinary construction for folding-machines.

In order to prevent such a vibration of the tapes as will let the sheets over the top of the stop, I have applied a roller or plate, X, as shown at Figs. 10 and 11, which will prevent such vibration of the tapes as to let the sheets over the stop.

I have shown the guide-fingers and stop for cumulating sheets with a folder; but it is evident that the folding path may be omitted and the cumulated sheets be permitted to pass out between the rollers E F to a fly and be laid in that manner on a fly-table, and the machine may have both provisions, so that in case the folder gets out of order that portion of it may be stopped and the cumulated sheets be permitted to pass over it. The form shown and described is the one which I deem best in practical use; but by giving the upper set of tapes a heavy downward pressure, or by putting both sets in a bent or curved position where the cumulation takes place, there will be sufficient pressure for the upper tapes to cumulate at the top instead of from below, and I do not limit myself to cumulating from below, although I deem that the best for straight-running tapes, and I deem straight-running tapes preferable to running them on a curve or an angle or to giving to the upper set an extra pressure.

When the dividers or guides b' or b'' are used their form causes them to hold up the rear edges or ends of the stop sheets and to guide the advancing sheets under the preceding stopped ones without any rear extension or heel.

The rod l , for operating the stop rod or shaft i , may be made to work direct against the cam or disk M by crossing to its opposite side and properly bending its end.

The shaft or roller J revolves in an opposite direction to the breaking roller or shaft D, causing all of the sheets to pass between the two shafts or rollers.

What I claim as new, and desire to secure by Letters Patent, is as follows:

1. The combination of the tapes r s with the breaking-roller D, dividing-roller J, and a divider or switch, substantially as specified.

2. The combination, with the upper and lower tapes, of a divider for directing the front edge of an advancing sheet past or by the rear edge of a sheet which is stopped between the tapes, substantially as described.

3. The combination, with the upper and lower tapes, of a stop for arresting the passage of the first sheet between the tapes, and a divider for directing the front edge of the second sheet past or by the rear edge of the stopped sheet, substantially as described.

4. The combination, with the cutting-rollers at the front end of the machine and the first pair of folding-rollers at the rear end thereof, of the upper and lower tapes, r and s , the roller J, the stop j , for arresting the movement of the first sheet between the tapes, and the divider for directing the front edge of the succeeding sheet or sheets past the rear edge of the stopped sheet, substantially as described.

5. The method of cumulating printed sheets of paper by stopping the first sheet within moving tapes, then guiding and passing the following sheet or sheets under or onto the stopped sheet or sheets, holding the stopped sheets between the tapes until the desired number of sheets are cumulated, then removing the stop from the path of travel and permitting the cumulated sheets to be moved by the tapes by the employment of a divider, tapes, and stop, substantially as described.

CONRAD KAHLER.
